UNITED STATES PATENT OFFICE.

JAMES L. G. BALLARD, OF WADEVILLE, NORTH CAROLINA.

CAR-COUPING.

1,125,252.

Specification of Letters Patent. Patented Jan. 19, 1915.

Application filed April 7, 1914. Serial No. 830,224.

To all whom it may concern:

Be it known that I, JAMES L. G. BALLARD, a citizen of the United States, residing at Wadeville, in the county of Montgomery, State of North Carolina, have invented certain new and useful Improvements in Car-Couplers; and I do hereby declare the following to be a full, clear, and exact description of the invention, such as will enable others skilled in the art to which it appertains to make and use the same.

This invention relates to new and useful improvements in car couplings and has for one of its objects to provide a coupling of this character wherein novel and efficient means are employed which, when the cars are moved to coupling position, will automatically operate to couple the cars.

A further object of the invention resides in the provision of an automatic coupling that is simple in construction, positive in operation and one in which the cost of production may be reduced to a minimum.

With the above and other objects of similar nature in view, the invention consists in the construction, combination, and arrangement of parts set forth in and falling within the scope of the appended claims.

In the drawings: Figure 1 is a fragmentary view of adjacent ends of two cars, with the invention applied thereto and shown in coupled position; Fig. 2 is a longitudinal section through the coupling with the parts shown in uncoupled position; Fig. 3 is an end view; and Fig. 4 is an enlarged fragmentary view showing the latch member in latching engagement with the draw head.

Referring now to the drawing, the coupling comprises a draw head 10 which is arranged upon a car in the usual manner and provided with the recess 11 and the vertically alined openings 12 through which a coupling pin is adapted to pass. Formed on the upper face of the draw head 10, is a lug or projection 13 having apertured ears 14 between which a lever 15 is adapted to be received, a pin 16 being passed through the ears and forming a pivotal mounting for the lever.

Pivotsly connected at the forward end of the lever 15 is a coupling pin 17, a latch member 18 being likewise pivotally connected at the rear end of the lever and adapted to pass through the slot 19 formed in the draw head 10 and project within the recess 11 thereof. For retaining the latch member

18 within the recess 11, there is formed on one face of the latch a notch 20, a spring 21 being arranged on the opposite face thereof and bearing against the rear wall of the slot 19 to urge the latch and bring the notched portion 20 into latching engagement with the front wall of the slot, as is clearly illustrated in Fig. 4.

It will be observed that when the latch 18 is in the position above described, the forward end of the lever 15 is swung upward on its pivot, thus raising the coupling pin 17 in the openings 12 to permit of the unobstructed passage of the shackle 22 into or out of the recess 11.

In operation, the shackle 22 passes within the recess 11 and engages and swings the latch 18 rearwardly in the slot 19, thereby throwing the notch 20 out of latching engagement with the front wall of the slot and releasing the latch. When the latch is released, the spring 23 which is disposed between the upper face of the draw head 10 and the rear end of the lever 15, swings said lever upwardly to withdraw the latch from the recess 11, the coupling pins 17 passing through the opening 24 in the shackle 22 to effect the coupling of the car. It will also be noted that the shackle 22 is provided with a collar 25 which engages the end of the draw head 10 to limit the movement of the shackle into the recess 11 and thus insuring the proper positioning of the opening 24 to receive the coupling pins.

To obviate the necessity for uncoupling the cars by hand, there is provided a crank 26 which is rotatably mounted in suitable brackets carried by the car and formed with the handles 27 by which it may be conveniently operated, said crank being adapted to engage and swing the rear end of the lever 15 downward on its pivot, to withdraw the coupling pins 17 from the shackle 22 and reset the latch.

From the foregoing it will be observed that there is provided a coupling of the character described, that is simple in construction, inexpensive to manufacture and one which is automatically operated to effect the coupling of the car.

What is claimed is:

In a car coupler, the combination with a drawhead provided with a recess and a slot communicating therewith, of a lever pivotally mounted on said drawhead, a latch pivotally carried at one end of the lever and

passing through said slot, a shoulder formed on said latch for locking engagement with a wall of the recess with the free end of the latch projecting within the latter, a spring 5 carried by the latch on the opposite side from said shoulder and engageable with a wall of the slot to force and retain the latch in locking position, a coupling pin carried by the other end of said lever, and a shackle

insertible within said recess to engage and release said latch whereby to couple the cars.

In testimony whereof, I affix my signature, in the presence of two witnesses.

JAMES L. G. BALLARD.
